UNITED STATES PATENT OFFICE

2,149,456

SEWING MACHINE

Frank W. Merrick, Boston, Mass., assignor to
United Shoe Machinery Corporation, Paterson,
N. J., a corporation of New Jersey

Original application June 30, 1934, Serial No.
733,182. Divided and this application August
25, 1936, Serial No. 97,839

8 Claims. (Cl. 112—47)

This invention relates to sewing machines, and particularly to machines for sewing strips to sheet material. As illustrated herein, the machine is organized for sewing a strip located edgewise with respect to the marginal portion of an insole blank in the manufacture of insoles of the type disclosed in Letter Patent of the United States No. 2,078,337, granted April 27, 1937, upon my application of which this application is a division.

Objects of the invention are to enable strips to be attached to sheet material in upstanding relation thereto, and to facilitate the manufacture of insoles having lasting lips comprising strips secured in upstanding relation thereto at a predetermined distance from their edges.

The invention comprises means for presenting a strip edgewise to a sheet, and stitch-forming mechanism operated to pass stitches through the strip from edge to edge and through the sheet to secure the strip and sheet together. As illustrated, and as used in making insoles, the machine is provided with means for guiding the strip in predetermined location with respect to the edge of an insole blank, and for presenting a strip and blank to the sewing mechanism so that the needle will pass edgewise through the strip and through the blank. As illustrated, means is provided for varying the position of the strip with respect to the edge of the blank. Also in the illustrated machine a movable intermittent grip device is provided for applying pressure intermittently to the strip to hold the strip while the needle is passing through it and to release the strip after the needle has passed through it. This device is preferably operated, as illustrated, by the usual presser foot with which the machine is provided.

In the drawings,

Fig. 1 is a plan of the "top" side of an insole with the attached upper securing strips according to the invention;

Figs. 2 and 2A are sections, on an enlarged scale, on the lines 2—2 and 2A—2A respectively of Fig. 1;

Fig. 2B illustrates an insole with a modified form of strip, and corresponds to a section on the line 2—2 of Fig. 1;

Fig. 2C is a transverse cross-section of the strip according to Fig. 2b before it is applied to the insole;

Figs. 3 and 4 are sections on the line 2—2 of Fig. 1, illustrating steps performed in the method of making the shoe;

Fig. 3A is a fragmentary section, corresponding

to Fig. 3, showing the modified form of insole and strip according to Figs. 2B and 2C;

Fig. 5 is an elevation, with parts in section, of a machine for making the insole according to Figs. 1 and 2;

Fig. 6 is a section on the line 6—6 of Fig. 5;

Fig. 7 is a front elevation, on an enlarged scale, of the head of the machine shown at the upper left hand corner of Fig. 5;

Fig. 8 is a side elevation of Fig. 7, with parts in section and parts omitted;

Fig. 9 is a section on the line 9—9 of Fig. 7;

Fig. 10 is a section on the line 10—10 of Fig. 8, with parts omitted and parts in elevation;

Fig. 11 is a section on the line 11—11 of Fig. 5;

Figs. 15 and 16 are sections on the lines 15—15 and 16—16 respectively of Fig. 13;

Fig. 17 is a side elevation of a spring member used in connection with the work guide;

Figs. 18, 19 and 20 are front elevations, on an enlarged scale, with parts in section and parts omitted, of the feeding mechanism and associated parts, each of these figures showing the parts in different operative positions;

Figs. 21 and 22 are plans, on an enlarged scale, showing the insole guide in different operative positions;

Fig. 23 is a plan according to Fig. 21 with the presser foot and insole omitted;

Fig. 24 is an elevation of a detail of one form of work support and work feeding mechanism;

Fig. 25 is a side elevation, with parts omitted, of a modified form of work support and work feeding mechanism;

Fig. 26 is a front elevation according to Fig. 25;

Fig. 27 is a plan of the strip gripper and associated parts according to Figs. 25 and 26;

Figs. 28 and 29 are elevations according to Fig. 25, with parts in section, showing the strip gripper in different operative positions; and

Fig. 30 is a fragmentary section, corresponding to Fig. 29, showing the relative positions during the sewing operation of the insole and the modified form of strip according to Figs. 2B and 2C.

According to one form of the invention, the insole 1 has secured thereto, at opposite sides thereof, strips 3 of suitable material such as leather, or leather substitute such as paper compositions and the like, these strips being of relatively small size, for example, but without limit.

tation thereto, in the order of $\frac{1}{8}$ " thick and from $\frac{1}{8}$ " to $\frac{1}{4}$ " high. If desired, the insole may comprise a heel and shank stiffener which as shown is in the form of a thin sheet 4 of fiber board or the like cemented or otherwise secured to the main portion of the insole before applying the strips.

As illustrated by Figs. 1, 2 and 3, the strips are of rectangular cross-section and are placed edge-wise against the insole and are sewed thereto by lines of stitching 5, the stitches 1 of which preferably pass through the insole and from edge to edge through the strip. By this construction rigid abutments are formed for enabling an upper 9 to be drawn over a last 11 and to be secured to the abutments by staples or other securing means 13.

In the form of the invention illustrated by Figs. 2B and 2C the strips 3 are inclined inwardly from the edges of the insole, which construction may be desirable to facilitate the stapling operation when employing certain forms of stapling instrumentalities. For this purpose the edges 3 of the strips contacting with the insole surface 25 are beveled. The strips may be held normally to the insole during the sewing operation and when sewed the tension of the stitches acts to draw the strips into their inclined positions illustrated.

Before the upper is worked into lasted position 30 and secured to the strips 3 forming the insole rib, for example by staples or the like, cement may be applied to the portion of the insole between its edges and the strips 3, or to the corresponding portions of the uppers, or both, the 35 staples holding the uppers in place until the cement dries. This cementing operation may be facilitated, if desired, by subjecting to pressure that portion of the uppers which overlaps the insole. After the uppers are cemented in position, as indicated in Figs. 3 and 3A, the strips 3 and excess portions of the uppers may be severed by a trimming operation, leaving the shoe in the condition illustrated by Fig. 4 preparatory to applying the sole. The method of utilizing my novel 45 insole may be substantially as disclosed in United States Letters Patent No. 1,932,545, granted October 31, 1933, upon an application filed in the name of George Goddu.

It will be observed that the stitches passing 50 through the strips edgewise, being under tension and of considerable diameter relative to the thickness of the strips, draw the latter tightly against the insole to form a substantially rigid abutment, which eliminates all substantial tendency of the abutment to bend or tilt during the operation of applying the uppers. Thus is avoided the common defect of prior constructions.

It will also be understood that the invention is not limited to insoles or shoes, but comprehends 60 any construction in which a strip is sewed edge-wise to a sheet.

Figs. 5 to 24 of the drawings illustrate one form of the machine for performing the sewing operation.

65 As illustrated, this machine comprises a frame having a base portion 15 integrally formed with a vertical standard 17, the upper end of which latter is integrally formed with a horizontal arm 19.

70 At the forward end of the arm 19 is shown an oscillating head 21 in which is mounted a vertically reciprocating bar 23 carrying an awl 25 and a second reciprocating bar 27 carrying a presser foot 29. At the lower portion of the machine 75 the base 15 carries a fixed bracket 31 in

which is mounted a vertically reciprocating bar 33 carrying a needle 35. A second fixed bracket 37 at this portion of the machine carries a strip guide plate 39 and a mechanism comprising an insole guide roller 41. At this portion of the machine is also mounted a work support, generally indicated (Fig. 5) at 43, which oscillates in phase with the head 21 so as to maintain the support in substantially fixed relation to the awl and presser foot.

The oscillatory head 21, which carries the awl and presser foot, as shown has integrally formed therewith a shaft 45 which is mounted for oscillation in the upper horizontal arm 19 of the frame of the machine. The drive shaft 47 for the machine extends through and at its forward end is journaled in the shaft 45. At its rearward end it is journaled at 49 in the frame of the machine, and is provided with a belt pulley 51 so that it may be driven by power.

As shown, interiorly of the standard 17 is a lever 53 fulcrumed on a pin 55 (Fig. 5), the upper end 57 of the lever being bifurcated and cooperating with a cam 59 on the shaft 47 so that when the latter is rotated the lever will be oscillated. 25 The lower bifurcated end 61 of the lever 53 embraces a pin 63 carried at the upper end of an arm 65 which is fixed to an oscillatory shaft 67 journaled in the base of the machine, as illustrated in Figs. 6 and 11. The outer end of the 30 pin 63 is embraced by the bifurcated end 69 of an arm 71 which is fixed to the rearward end of the shaft 45 which carries the oscillating head 21, as a result of which when the shaft 47 is rotated the head 21 will be oscillated.

Referring particularly to Figs. 5, 7 and 8, the awl bar 23, which is mounted for reciprocation in the oscillating head 21, has fixed to it the laterally projecting pin 73 which is connected by a link 75 to a crank pin 77 laterally projecting 40 from a crank 79 on the front end of the shaft 47 so that when the latter is rotated the awl bar will be reciprocated in the oscillating head 21.

The presser foot bar 27, which also is mounted for reciprocation in the oscillating head 21, at 45 its upper end has fixed thereto a collar 81 serving as one abutment for a helical compression spring 83, the other abutment 85 of which is fixedly carried by the oscillating head 21. The spring 83 operates to urge the presser foot 29 toward the work. For holding the presser foot in permanently raised position at the will of the operator a lever 87 pivoted to the arm 19 at 89 is provided. The right hand end of the lever 87, as viewed in Fig. 5, has attached thereto a link, 55 cord, wire, or the like 91 which may be pulled downward by means of a foot pedal or the like (not shown) so as to raise the left hand end of the lever to cause a projection 93 thereon to engage the collar 81 and raise the presser foot 60 bar.

As illustrated in Fig. 9, for reciprocating the presser foot bar, the latter has slidably mounted thereon a block 95 to which is pivotally mounted at 97 a jaw 99 adapted to clamp the block to the presser foot bar. The jaw 99 is operatively connected, by means of a toggle strut 101, to a lever 103 pivoted at 105 between a pair of arms 107 carried by the block 95, between which arms the toggle strut and the jaw 99 are also positioned. 65 The lever 103 has a wiping contact, as shown, with a finger 109 fixedly carried by a rock shaft 111, which latter is supported by the pintles 113 carried by the opposite side walls 115 of the head 21. As shown (Fig. 8), the rock shaft 111 is pro- 70 75 75

vided with an arm 117 connected at its outer end by a link 119 to a pin 121 mounted in a block 123 fixedly carried by the reciprocating awl bar 23. By this construction when the awl bar moves upward the finger 109 is caused to wipe against the lever 103 and thus through the toggle strut 101 force the clamping member 99 against the presser foot bar 27 which locks the block 95 to the presser foot bar and causes upward movement thereof. Upon downward movement of the awl bar the clamping member 99 is released from the presser foot bar, and the latter descends due to the action of the helical compression spring 83. By reason of this construction the presser foot is given a constant lift relative to the work, and automatically compensates for work of different thicknesses.

As illustrated, for reciprocating the needle bar 33 which, as hereinbefore mentioned, is reciprocally mounted in the bracket 31 fixedly carried by the base of the machine, the drive shaft 47 is provided with an eccentric 125 which operates an eccentric rod 127 connected at its lower end to the crank pin 129 adjustably mounted on the end 25 of a crank 131 fixedly secured to a rock shaft 133 journaled in the base of the machine (Figs. 5, 6, 11 and 13). At its forward end the rock shaft 133 is provided with an offset crank arm 135 (Fig. 6) which at its outer end carries a crank pin 137 30 on which is pivotally mounted the lower end of a connecting rod 139 (Figs. 5, 6 and 13), the upper end of which connecting rod is pivotally connected to a pin 141 fixedly secured to and laterally projecting from the needle bar 33. By this construction when the shaft 47 is rotated the needle bar will be reciprocated.

As shown, the oscillating shaft 67 (Figs. 5, 6, 11, 13 and 14) at its forward end is provided with a crank arm 143, which latter at its free end has a forwardly projecting portion 145, and on the end of the latter is a vertically projecting arm 147 which carries the work support.

As shown (Figs. 13, 14, 18, 19, 20, 23 and 24) the work support 43 comprises a bar 149 secured by a bolt 151 to the upper end of the oscillatory arm 147. Integrally formed with the upper end of the bar is a laterally projecting V-shaped bracket the side members 153 of which have upwardly projecting studs 155 on which are mounted V-edged rollers, the upper surfaces 157 of the rollers being substantially horizontal at their highest portions so as to form a support for the insole or other sheet, while the lower surfaces 159 of the rollers are substantially vertical at their highest portions to form between them a notch for guiding the strip. The upper edge of the V-shaped bracket as shown is flattened to provide a seat 161 (Fig. 24) for the bottom edge of the strip, and this portion of the bracket is 50 provided with an elongated slot 163 to permit passage of the awl and needle. As shown, the work engaging portion 165 of the presser foot 29 is provided with a slot 167 in registry with the slot 163 in the work support for permitting passage of the awl and needle. The strip guide plate 39 carried by the fixed bracket 31 (Figs. 5, 13 and 16) is provided with a notch 169 of approximately the same dimensions as the space between the two rollers at the upper portion of the work support. The strip passes through this notch, and the latter serves to guide it to the space between the rollers.

The roller 41 for guiding the insole in the present embodiment of the invention is operatively carried by the vertical fixed bracket 37. As

shown (Fig. 16), the bracket at its upper end is provided with the spaced, upstanding portions 171 which are formed at their upper ends to provide dove-tail grooves 173 in which is slidably mounted a plate 175, the latter at its lower side having a portion 177 to fit these grooves. The plate may be clamped in adjusted position relative to the bracket 37 by means of a bolt 179, this bolt also passing through the slotted opening 181 in the plate 39 and serving also to hold the plate in adjusted position relative to the bracket. Tightening the bolt 179 causes the portions 171 to spring toward each other sufficiently to cause the grooves 173 to bind against the corresponding portion 177 of the plate 175 to hold the plate in adjusted position.

As illustrated, the plate 175 is provided with a stud 183 (Fig. 15) on which is mounted a lever 185 (Fig. 22) having a handle portion 187. Pivoted to a stud 189 carried by the left hand end of the lever 185 is an arm 191, the outer end of which arm carries a stud 193 on which is rotatably mounted the roller 41. At the under side of the roller the stud 193 is provided with a projection 195 which enters a longitudinally extending slot 197 in the plate 175. The arm 191 at the right hand side of the stud 189, as viewed in Figs. 21 and 22, is provided with an extension forming a V-shaped opening having the sides 199 and 201 which cooperate with a projecting pin 202 which may be inserted in any of the series of holes 203 formed in the lever 185.

When the parts are in the position shown by Fig. 21, the side 201 of the V-shaped opening in the arm 191 contacts with the pin 202. In this position of parts the roller 41 is at the extreme left hand end of its movement and will cause the strip to be spaced the minimum distance from the edge of the insole. When the handle 187 is moved by the operator into the position shown by Fig. 22, the side 199 of the V-shaped opening will engage with the pin, under which conditions the roller 41 will be moved to the right and space the strip farther from the edge of the insole. By inserting the pin in different holes 203 the travel of the roller 41 under the influence of the handle 187 may be varied, and this handle may be operated during the sewing operation to cause the strip to be placed at different distances from the edge of the insole at its different positions on the insole. When the roller is shifted, the strip gradually moves toward or away from the insole edge as the sewing operation continues due to the fact that the insole is held to the strip by the stitches and the awl or needle which may be in the work.

For adjusting the position of the stud 183, so as to vary the maximum and minimum distances the strip is spaced from the edge of the insole, the plate 175 at its outer end is provided with a slot 205 through which the lower reduced diameter portion 206 of the stud extends, as is clearly illustrated in Figs. 15, 21 and 22, which slot permits the stud to be moved longitudinally of the plate and to be clamped in adjusted position by means of a nut 207. Conveniently between the head 209 of the stud and the lever 185 is positioned a split helical washer or spring 211, which latter acts to hold the lever frictionally in its several positions of adjustment.

Any suitable type of needle may be employed, as, for example, one of the hooked, spiral groove type, shown in applicant's Patent No. 703,941, July 1, 1902, for forming a chain stitch. When this type of needle is employed, a finger 213 hav-

ing an eye 218 (Figs. 10 and 20) may be provided, through which eye the thread passes, the finger being operated to wrap the thread about the needle when the parts are in the position shown by Fig. 20. As illustrated, for operating the finger the same is pivoted by pintles 217 (Figs. 5, 8, 10 and 12) to a rock shaft 219 mounted in a bearing 221 formed in a downwardly projecting lug 223, which latter is formed integrally with the horizontal arm 18 of the frame of the machine. As shown, the upper end of the finger 213 has pivotally mounted thereon a V-shaped cam follower block 225 cooperating with a V-shaped cam groove 227 formed on the periphery of the cam disk 228 (Figs. 5, 8 and 10) fixedly mounted on the forward end of the shaft 41. As illustrated, this cam groove has a laterally offset portion 229 and a slightly flattened portion 231 of angular extent A (Fig. 10), which portions 20 conjointly act to give the lower end of the finger 213 a three dimensional oscillatory motion for wrapping the thread about the end of the needle. For holding the finger 213 in operative relation to the cam groove 227, the rock shaft 219 has fixed thereto an arm 232, the upper end of which arm rides on the periphery of a cam 233. This cam is fixed to the shaft 41 and has a profile of such shape as will cause the cam follower block 225 to be maintained in the cam groove 227.

30 In employing the machine so far described for sewing the strip to the insole, the presser foot is raised by manipulation of the lever 87 and the strip inserted through the notch 168 in the plate 39, as indicated in Fig. 23. The insole is then inserted beneath the presser foot with its edge against the roller 41, as indicated in Fig. 21, and the presser foot is then released and the machine placed in operation. Preferably the sewing of the strip is started at the toe end of the insole, 40 and, when the shank portion thereof is reached, if the strip is to be sewed farther from the insole edge at that portion than at the toe portion the handle 181 is thrown into the position shown by Fig. 22 to retract the roller 41.

45 The operation of the feeding of the strip and sheet may be best understood from Figs. 18, 19 and 20. When the parts are in the position shown by Fig. 18 the awl 25 descends and perforates the insole and strip. The arm 147 and head 21 then oscillate to move, to the left a distance of one stitch, those parts which are carried thereby adjacent the work. This movement places the awl in alignment with the needle, as shown in Fig. 19, and during this movement, the insole and strip being gripped between the presser foot 165 and the V-shaped head and rollers of the work support, and the awl being in the work, the insole and strip are moved to the left a distance of one stitch. The awl is then withdrawn 55 and the needle 35 passed through the awl hole, as shown in Fig. 20, whereupon the presser foot is raised to release the work, and the head 21 and arm 147 oscillate to the right again to bring the machine parts into their initial position shown by Fig. 18. The thread looper 213 wraps the thread about the needle when the parts are in the position shown by Fig. 20, whereupon the needle descends at approximately the end of the return stroke of the arm 147 and head 21 and, 70 with the particular form of needle referred to, pulls a loop of thread through the work.

Conveniently provision is made for varying the degree of oscillation of the head 21 and arm 147 so as to vary the length of the stitches. As illustrated, for this purpose the lever 53 (Figs. 5 and

11) may be formed with an arcuate slot 232 in which is slidably mounted a block 233 rotatably mounted on the pin 55, which pin serves as a fulcrum for the lever, the pin being fixedly carried by a lever 234 pivoted on a pin 235 carried by the frame of the machine. The lever 234 as shown projects through a slot 236 in the frame of the machine to provide a handle portion thereon accessible to the operator. Any suitable means, for example, a split resilient bearing sleeve 10 237 for the lever about the pin 235, may be provided for holding the lever 234 in its adjusted positions. As will be obvious, shifting the position of the lever 234 varies the degree of oscillation of the pin 53 and hence the degree of oscillation of the shaft 61 carrying the arm 37 and the degree of oscillation of the shaft 41 carrying the head 21.

In Figs. 25 to 28 is illustrated a modified form of work gripping mechanism which is particularly useful in cases where relatively high strips 3 are employed, say those exceeding $\frac{1}{8}$ " in height. According to this form of the invention, the strip is positively gripped to the work support during the feeding movement thereof in one direction and released during the return stroke. As shown, the arm 147 carries a work support in the form of an angle bracket having a vertical leg 238 attached to the arm, and a horizontal leg 241 carried by the leg 238. At the side of the leg 238 is integrally carried a bracket 243 having the ears 245 between which is placed the base portion 247 of a clamping finger 249, this base portion being pivotally mounted on a pin 251 carried by the ears 245. Conveniently for limiting the throw of the finger 249 in one direction, the base portion 247 of the finger is provided with a flattened portion 253 which cooperates with an adjustable screw pin 255 carried by the bracket 243. As shown, the upper horizontal leg 241 of the work support is provided with an upstanding lug 257 positioned at one side of the slot 259 formed in the work support for permitting passage of the awl and needle. At the opposite side of the slot the finger 249 has an upstanding portion 261. Normally the presser foot 165 when the work is not inserted will rest upon the upper edge of the upstanding lug 257 on the work support, as shown in Fig. 25. When a strip 3 and insole 1 are inserted with the presser foot in raised position, as shown in Fig. 28, the sheet will rest upon the upper end of the upstanding portion 261 of the clamping finger 249. When the presser foot is lowered to engage the work, as shown in Fig. 29, the presser foot causes the upstanding portion 261 of the finger to be pressed downward to cause the finger to swing about its pin 251 to clamp the strip between the upstanding portions 257 and 261. During the operation of the machine, when the arm 47 and presser foot 29 move in one direction to feed the work, with the presser foot bearing against the upper side of the insole, both the strip and the insole are securely clamped to move with the presser foot and work support. During the return stroke the presser foot is in its raised position, as shown in Fig. 28, and both the insole and strip are released from the work support and are held by the needle which at that time engages the work.

The relative position of the insole and strip 3 during the sewing operation will be understood from Figs. 21, 22, 23 and 29, care being taken when employing the beveled-edge strip according to Fig. 2C to insert the strip with its beveled edge upward and facing the median line of the insole, as indicated in Fig. 30, whether employing 75

the modification of the machine according to Fig. 24 or Fig. 30.

It will be understood that the invention is not limited to the use of the particular type of needle referred to or to a chain stitch machine, and that wide deviations may be made from the forms of the invention herein illustrated and described without departing from the spirit of the invention.

Having thus described the invention, what I claim as new and desire to secure by Letters Patent is:

1. A machine for sewing strips to sheet material having, in combination, means for presenting the strip edgewise to the sheet, stitch forming mechanism operative to pass stitches through the sheet and from edge to edge through the strip for securing them together, means for feeding the sheet and strip relative to said stitch forming mechanism comprising means for presenting the strip edgewise to said mechanism, and means operating upon the sheet for positioning it relative to said stitch forming mechanism for causing the strip to be sewed to the sheet in predetermined spaced relation to the edge of the sheet, the last mentioned means having provision for varying the spacing of the strip from the edge of the sheet during the sewing operation.

2. A machine for sewing strips to sheet material having, in combination, stitch forming mechanism, means for presenting the strip edgewise to the sheet comprising a support for the strip and sheet and a cooperating presser member for holding them in operative relation to said support, means for moving said support and presser member in one direction from an initial position to a final position for feeding the sheet and strip a distance of one stitch and then releasing said presser member and returning it and said support to said initial position, said stitch forming mechanism being operative to hold said sheet and strip in said final position substantially until the succeeding feeding movement of said support and presser member.

3. A machine for sewing strips to sheet material having, in combination, stitch forming mechanism comprising a reciprocatory needle and awl, means for presenting the strip edgewise to said sheet comprising a support for the sheet and strip and a cooperating presser member for holding them in operative relation to said support, means for passing said awl through the sheet and edgewise through the strip, means for moving said awl while in the sheet and strip, and said support and presser member, for feeding the strip

and sheet the distance of one stitch, and for withdrawing said awl and passing said needle into the awl hole and maintaining said needle in said hole while returning said presser member and support.

4. A machine for sewing strips to sheet material having, in combination, means for presenting the strip edgewise to said sheet, stitch forming mechanism operative to pass stitches through the sheet and from edge to edge through said strip for securing them together, feeding means for said strip comprising a movable support having means for engaging the sides and an edge of said strip, and a presser member for holding the sheet in operative relation to the other edge of said strip.

5. A machine for sewing strips to sheet material having, in combination, means for presenting the strip edgewise to said sheet, stitch forming mechanism operative to pass stitches through the sheet and from edge to edge through said strip for securing them together, feeding means for said strip comprising a support for one edge of said strip having rollers for engaging the sides of the strip and adapted to support the sheet substantially in contact with the opposite edge of the strip, a presser device, and means for causing the latter intermittently to press the sheet against said rollers.

6. A machine for sewing strips to sheet material having, in combination, means for presenting the strip edgewise to the sheet, stitch forming mechanism operative to sew the sheet to the strip, and work feeding means comprising a movable intermittent grip device for engaging the sides of the strip.

7. A machine for sewing strips to sheet material having, in combination, means for presenting the strip edgewise to the sheet, stitch forming mechanism operative to sew the sheet to the strip, work feeding means comprising a movable intermittent grip device for engaging the sides of the strip, and a presser device for the work cooperating with said grip device for operating it.

8. A machine for sewing strips to sheet material having, in combination, means for presenting the strip edgewise to said sheet, stitch forming mechanism operative to sew the sheet to the strip, work feeding means comprising a movable intermittent grip device for engaging the sides of the strip, said grip device having an operating member adapted to engage the sheet, and a presser foot for engaging the sheet and operating said grip device.

FRANK W. MERRICK. 55

CERTIFICATE OF CORRECTION.

Patent No. 2,149,456.

March 7, 1939.

FRANK W. MERRICK.

It is hereby certified that error appears in the printed specification of the above numbered patent requiring correction as follows: Page 1, first column, line 52, after "sections" insert through the shoe and last, corresponding to the sections; and that the said Letters Patent should be read with this correction therein that the same may conform to the record of the case in the Patent Office.

Signed and sealed this 26th day of September, A. D. 1939.

(Seal)

Henry Van Arsdale,
Acting Commissioner of Patents.
